(57) **CLAIM**

The ornamental design for a portion of mesh basket, as shown and described.

DESCRIPTION

FIG. 1 is a front view of a first embodiment of a portion of mesh basket of our new design, the rear view being substantially identical;

FIG. 2 is a right side view thereof, the left side view being substantially identical;

FIG. 3 is a top view thereof;

FIG. 4 is a bottom view thereof;

FIG. 5 is a front view of a second embodiment of our new design, the rear view being substantially identical;

FIG. 6 is a right side view thereof, the left side view being substantially identical; and,

FIG. 7 is a top view thereof.

The broken line showing in the drawings is illustrative and forms no part of the claimed design.

1 Claim, 5 Drawing Sheets
